COMBINATION CHAIR AND DESK OR SIMILAR ARTICLE

Max E. Brafman, New York, N. Y.

Application September 1, 1948, Serial No. 148,413

Term of patent 14 years

(Cl. D33—11)

To all whom it may concern:

Be it known that I, Max E. Brafman, a citizen of the United States of America and a resident of the city, county, and State of New York, whose post-office address is 210 West 70th Street, New York city, N. Y., have invented a new, original, and ornamental Design for Combination Chair and Desk or Similar Article, of which the following is a specification, reference being had to the accompanying drawing, forming a part thereof, in which:

Figure 1 is a perspective view of the combination chair and desk or similar article, showing my new design;

Figure 2 is a top plan view thereof on slightly reduced scale; and

Figure 3 is a side elevational view thereof on the same reduced scale as Figure 2.

I claim:

The ornamental design for a combination chair and desk or similar article, as shown.

MAX E. BRAFMAN.
